AIRPLANE

Lessiter C. Milburn, Towson, Md., assignor to
The Glenn L. Martin Company, Baltimore,
Md.

Application November 1, 1932. Serial No. 640,715

5 Claims. (Cl. 244—14)

My invention relates to multi-engine types of propeller driven aircraft.

Airplanes upon which a plurality of propeller units are mounted in a plurality of horizontally spaced geometric planes are longitudinally stable while in flight with a given setting of the horizontal member of a stabilizer system. The resultant of the several individual thrusts being in a given lever arm relation to both the center 10 of gravity of the airplane and the stabilizer system, failure of an auxiliary unit that is conventionally mounted above the main units so changes the turning moment that the nose of the airplane may be upwardly deflected to such 15 an extent so as to initiate a stall which may develop into a crash, particularly when the units are forwardly located in relation to the center of gravity. The turning moment about the center of gravity can eventually be counteracted by 20 a re-adjustment of the horizontal stabilizer but the available period of time within which to operate the related mechanism is insufficient to effectively counteract the stalling tendency.

The present invention mounts the propeller units not only in a certain relation to one another, and to the stabilizer system, but also to the centers of gravity so that either the failure or elimination of an engine in an upper geometric plane, one which I designate as an auxiliary propeller unit, will not affect the adjusted longitudinal stability of the airplane. The thrust of the auxiliary propeller is so directed as to produce a downward moment upon the horizontal member of the stabilizer system; thus overcoming the normal tendency to nose over while in flight with all engines functioning. Functional failure of the auxiliary unit results both in a reduction of thrust and a corresponding reduction of the downward component upon 35 the stabilizer, and therefore neither the longitudinal stability nor the direction of flight of the craft is altered. Moreover, because the center of gravity of the auxiliary unit lies substantially over the center of gravity as well as in 40 the plane of symmetry of the airplane, the auxiliary unit can be removed without materially affecting either the center of buoyancy of a seaplane while floating upon water and taking off, or the inherent stability of the airplane while 45 flying.

The principal object of my invention is therefore to prevent a stall being initiated by functional failure of a propeller unit that is mounted above the main power units of an airplane.

55 Another object is to render it unnecessary to

re-adjust the horizontal stabilizer because of reduced thrust while idling an auxiliary propeller unit.

Another object is to permit removal of an auxiliary propeller unit from an airplane without affecting the inherent longitudinal stability 60 while in flight.

Another object is to permit removal of an auxiliary propeller unit from a seaplane without affecting the inherent take-off characteristics. 65

Referring to the drawings:

Fig. 1 is a plan view of a flying boat type of airplane that is equipped with two main propeller units together with an auxiliary propeller 70 unit.

Fig. 2 is an end elevation of the airplane shown in Figure 1.

Fig. 3 is a side elevation of the airplane shown in Figures 1 and 2. 75

In the drawings; cargo body 10 is sustained by surface 11 while flying. Tail portion 12 includes a stabilizer system having a horizontal member 13, an elevator 14, and rudders 15—15' under control of the pilot through conventional mechanisms; together with two vertical fins 16—16', all being mounted upon tail portion 12. The center of gravity of the craft is indicated at 17 when empty, and at 18 when loaded; and the center of buoyancy while floating upon water is 80 indicated at 19. Main propeller units 20—20' are mounted in equilateral relation to the body. The discs of the main propellers are indicated at 21—21', but they may or may not be located in a common perpendicular plane as shown in 85 the drawings. Auxiliary propeller unit 22 is mounted substantially over the center of gravity and the center of buoyancy, as well as substantially in equilateral relation to the symmetry of the airplane; the disc of the auxiliary propeller 90 is indicated at 23, and the center of gravity of the unit is indicated at 24. The geometric plane of the disc is parallel to the leading edge of surface 11 as well as angularly related to the main propeller discs; angle 30 being such that resultant thrust line 31 of the main propellers intersects thrust line 32 of the auxiliary propeller at a point 33 either upon or above and substantially over the horizontal stabilizer and between the 95 vertical fins. The maximum stabilizing effect 100 of the auxiliary propeller is attained when the thrust lines intersect the horizontal member of the stabilizer system.

The foregoing description of my invention, together with the accompanying drawings, will 110

make it clear to those skilled in the art of aviation that when the center of gravity of an auxiliary propeller unit is located substantially over that of the airplane upon which it is mounted substantially in the manner herein set forth together with the aforesaid thrust line relations, then the longitudinal stability and the take-off characteristics of the craft are not deleteriously affected whether or not the unit is functioning; or the unit can be dismounted without deleteriously affecting either the take-off or flight characteristics of the craft including the unit. Conversely; the invention mounts an auxiliary propeller power unit upon an airplane having a conventionally mounted power plant and a rearwardly located stabilizer system so that the initial power capacity can be augmented without materially affecting the inherent stability of the craft while flying.

20 I claim:

1. In an aircraft: a sustaining surface; a cargo body sustained by said surface, said body having a tail portion; a stabilizer system connected to said tail portion; a plurality of main propeller units mounted in equilateral relation to said body; an auxiliary propeller unit mounted above said main units, the center of gravity of said unit being located substantially over the center of gravity of said aircraft; the plane of the auxiliary propeller disc forming an acute angle with a plane that includes a plurality of main propeller discs, and the thrust line of said auxiliary propeller intersecting a horizontal member of said stabilizer system.

35 2. In an aircraft: a sustaining surface; a cargo body sustained by said surface, said body having a tail portion; a stabilizer system connected to said tail portion; a plurality of main propeller units mounted in equilateral relation to said body, the propellers being ahead of the leading edge of said surface; an auxiliary propeller unit mounted within the plane of symmetry of said aircraft, the propeller being rearward of the leading edge of said surface; the disc of said auxiliary propeller being angularly related to the discs of said main propellers; and the thrust line of said auxiliary propeller intersecting both the resultant thrust line of said main propellers and a horizontal member of said stabilizer system.

3. In an aircraft: a sustaining surface; a cargo body sustained by said surface, said body having a tail portion; a stabilizer system connected to said tail portion; a plurality of main propeller units mounted in equilateral relation to said body; an auxiliary propeller unit mounted within the plane of symmetry of said aircraft, the propeller being rearward of the leading edge of said surface; the disc of said auxiliary propeller being angularly related to the discs of said main propellers; and the thrust line of said auxiliary propeller intersecting both the resultant thrust line of said propellers and a horizontal member of said stabilizer system.

4. In an aircraft: a sustaining surface; a cargo body sustained by said surface, said body having a tail portion; a stabilizer system connected to said tail portion; a plurality of main propeller units mounted in equilateral relation to said body, the propellers being ahead of the leading edge of said surface; an auxiliary propeller unit mounted within the plane of symmetry of said aircraft, the disc of said auxiliary propeller being angularly related to the discs of said main propellers; and the thrust line of said auxiliary propeller intersecting both the resultant thrust line of said main propellers and a horizontal member of said stabilizer system.

5. In an aircraft: a sustaining surface; a cargo body sustained by said surface, said body having a tail portion; a stabilizer system connected to said tail portion, said system including a plurality of vertical fins mounted upon a horizontal stabilizer; a plurality of main propeller units, said units being mounted in equilateral relation to said body; an auxiliary propeller unit mounted upon said sustaining surface within the geometric plane of symmetry, the center of gravity of said unit being substantially over the center of gravity of said body including said main units, the disc of the auxiliary propeller being angularly related to the discs of the main propellers; and the thrust line of the auxiliary propeller intersecting the resultant thrust line of the main propellers, the point of intersection lying between said vertical fins and over said horizontal stabilizer.
